UNITED STATES PATENT OFFICE

HARRY HORDES, OF JERSEY CITY, NEW JERSEY

SHOE LENGTHENER AND STRETCHER

Application filed January 16, 1928. Serial No. 247,249.

This invention appertains to a novel device for lengthening and stretching a shoe by the use of a single manipulating handle which is arranged exteriorly of the shoe.

5 One of the primary objects of the invention is to provide an improved shoe stretcher and lengthener embodying relatively adjustable heel and toe portions with means for adjusting the heel and toe portions by the use of a single turning screw, the handle portion of which is arranged exteriorly of the shoe.

Another important object of the invention is the provision of a single screw extending through the heel portion of a lengthener and stretcher and adjustably connected therewith having a bearing engagement with the fore part or toe section of the stretcher and lengthener whereby, upon adjustment of the screw, the sections can be moved relative to one another to bring about the stretching and lengthening operation.

A further object of the invention is the provision of novel means for connecting the adjusting screw with the fore part or toe section of the shoe lengthener or stretcher whereby proper adjustment of the lengthener and stretcher will be had without undue strain upon the various parts.

A further object of the invention is the provision of a novel shoe lengthener and stretcher which will effectively stretch the tip of a shoe as the shoe is being lengthened, the entire stretcher and lengthener being adapted to be made in various sizes and styles to accord to the shoes being operated on.

A still further object of the invention is to provide an improved shoe stretcher and lengthener of the above character, which will be durable and efficient in use, one which will be simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, in which drawings,

50 Figure 1 is a top plan view of the improved invention,

Figure 2 is a side elevation of the same, Figure 3 is a longitudinal section through the stretcher and lengthener taken on the line 3—3 of Figure 1 looking in the direction of the arrows,

55 Figure 4 is a fragmentary horizontal section through the stretcher taken on the line 4—4 of Figure 2 looking in the direction of the arrows,

Figure 5 is a transverse section through the 60 stretcher and lengthener taken on the line 5—5 of Figure 2 looking in the direction of the arrows.

65 Referring to the drawings in detail, wherein similar reference characters designate corresponding parts throughout the several views, the letter A generally indicates the improved shoe stretcher and lengthener which comprises a body 10 which is divided transversely to provide a fore part of toe section 11 and a rear part or heel section 12. These sections are so arranged that the same can be adjusted relative to one another and adjusting means, which is indicated broadly by the reference character 25, forms one of the salient features of the invention. The body 10 is preferably constructed from hard wood and is carved or otherwise formed to conform to the shape of a particular shoe or foot of a person and the body can be made 70 in different sizes and shapes if preferred.

75 The fore part or toe section 11 is preferably but not necessarily constructed from longitudinal sections 13 and 14 which are connected together rigidly by the use of suitable pins, screws, or the like 15. The inner faces of the longitudinal sections 13 and 14 are provided with recesses at their rear ends which define a pocket 16 in the rear part of the toe portion 11 of the body.

80 The rear part or heel section 12 can also be formed of longitudinal sections 17 and 18 which can also be rigidly connected together by the use of suitable pins or screws 18. This rear part is provided with a longitudinal bore 19 which is enlarged at its forward end as at 20 and a cross transverse bore 21.

85 The novel adjusting means 25 comprises a longitudinally extended shank 26 having a screw thread 27 extending for a portion of its 90 95 100

length. The outer end of the shank 26 is provided with a manipulating handle 28 which can be of any desired character or shape. The screw threaded portion 27 of the shank extends entirely through the longitudinally extending bore 19 and is threaded through a sleeve nut 29 arranged in said bore. The opposite sides of this sleeve nut 29 are provided with trunnions or arms 30 which are fitted within the transverse bore 21. This holds the sleeve nut in position against accidental movement.

The engagement of the forward end of the shank 26 with the toe section or fore part 11 forms one of the salient features of the invention and a block 31 is utilized which is fitted or otherwise arranged in the recess 16. Suitable holding screws 32 can be utilized for engaging the block to hold the same in position. The forward end of the shank extends through the block 31 and has its end pointed to provide a bearing, which engages a conical thrust bearing 33 formed in said block. As shown, a slot 34 is formed in said block and a suitable washer and pin 35 and 36 is carried by the shank and engages the rear wall of said opening and thus holds the shank against rearward movement relative to the block, while the thrust bearing prevents forward movement of the shank relative to the block. However, free turning movement of the shank is permitted.

It is to be noted that, upon turning movement of the shank in one direction, that the shank will be fed forwardly through the nut 29 which will consequently move the fore part 11 forwardly and the rear part or heel portion 12 rearwardly. When the shank is turned in the opposite direction the shank will be fed rearwardly and the toe and heel section will be brought together.

If preferred, a stop sleeve 37 can be riveted or otherwise secured to the shank 26 for engaging the sleeve nut 29 so as to limit the forward movement of the shank relative to the heel portion.

I also prefer to provide a guide means between the toe portion 11 and the heel portion 12 so as to eliminate strain on the adjusting means and to also hold the toe and heel sections in proper position. This guide means comprises spaced, longitudinally extending pins 38 which are anchored or otherwise secured to the forward face of the heel portion 12 directly below and on each side of the bore 19. The toe section or fore part 11 is provided with spaced longitudinally extending bores 39 which receive the guide pins and these pins are freely guidable in said bores.

From the foregoing description, it can be seen that I have provided a novel shoe lengthener and stretcher which will effectively stretch a shoe without injury thereto and with a minimum amount of exertion on the part of the operator of the device.

Changes in details may be made without

departing from the spirit or the scope of this invention but what I claim as new is:

A shoe stretcher comprising a pair of companion members shaped to conform to the interior configuration of a shoe, one of said members constituting a toe section and having a recess opening out through its rear face and extending forwardly and downwardly, the other of said members constituting a heel section and having a bore opening out through the inner and outer faces thereof and extending inwardly and downwardly in the same plane as the recess, a sleeve nut imbedded in said bore intermediate the ends thereof, an adjusting screw extending entirely through the bore and threaded in said sleeve nut and extending outwardly from said bore at the rear end of said heel section, a manipulating handle on the rear end of said screw, a thrust block fitted within said recess having a conical thrust bearing, means rigidly securing the block in said recess against movement, the forward end of the screw being tapered and rotatably mounted in said block and having its tapered end mounted in the thrust bearing, the block being provided with a recess, means carried by the screw and arranged in said recess for engaging the block to prevent rearward movement of the screw relative to the block, and guide pins carried by the heel portion for slidably engaging the toe.

In testimony whereof I affix my signature.

HARRY HORDES.
